ATTORNEY

UNITED STATES PATENT OFFICE.

ARTHUR R. GLIDDEN, OF SEATTLE, WASHINGTON.

WINDOW-SASH FASTENER.

Application filed December 9, 1925. Serial No. 74,271.

This invention relates to sash-fasteners, and has for its object the provision of efficient means adapted to be applied to the upper and lower sashes of a window for locking them together in their fully closed positions, and also in positions to afford openings at the top and bottom of a window for the purpose of ventilation.

The invention consists in the novel construction, arrangement and combination of parts hereinafter described and claimed.

In the accompanying drawing,—

Figure 1 is a perspective view of one side of a window frame, and of portions of the window sashes provided with fasteners embodying my invention. Fig. 2 is a vertical transverse sectional view of Fig. 1. Fig. 3 is a horizontal section on line 3—3 of Fig. 2.

20 In said drawing, the reference numeral 5 represents a side member of a window casing provided with ways 6 and 7 for the side rails 8 and 9 of the upper and lower window sashes, respectively.

25 Secured as by means of screws 10 to the side rail 8 of the upper sash is a vertically disposed metal bar or strip 11 having centrally of its width, a series of recesses 12 which are arranged in spaced apart relations longitudinally of the strip.

30 Said recesses are of less width than the strip and of substantially rectangular shape in front elevation to provide vertical bar elements 13 at opposite sides of the recesses and horizontal bar elements 14 between the successive recesses.

35 Cooperating with said strip is a metal latch which is indicated, generally, by 15. Said latch is formed to provide two arms 40 16 and 17 arranged in angular relation with each other, the extremities 18 and 19 of the respective arms being of a width to permit their entering the strip recesses 12.

45 Said arm extremities are, moreover, spaced vertically apart so as to be simultaneously engageable against the under and upper surfaces, respectively, of horizontal bars 14 of the strip 11. The latch 15 is mounted for rotary movement upon a base 50 plate 20 which is rigidly secured upon the top of the parting rail 21 of the lower sash by suitable means such, for example, as screws 22.

As shown, the latch arm 17 is seated upon

the plate 20 and is connected thereto in offset relation with the strip 11 by means of a pivot pin 23 extending through both the arm 17 and said plate.

55 By thus pivotally connecting the latch to the plate, the latch is capable of being swung about a vertical axis into and from its locking position, as represented by full lines in the drawing, with respect to the strip upon the upper sash thereby coupling the sashes together.

60 To disengage the sashes with respect to each other, the latch is swung into the position in which it is represented by dotted lines 15¹ in Fig. 3.

65 For the purpose of safeguarding the latch from being tampered with by a thin instrument inserted between the sashes from the outside of the window, I provide the base plate with a catch device for retaining the latch in its engaged position. To such end, the base plate 20 is slotted transversely as at 25 to provide a tongue 26 having a protuberance 27 adapted to engage against a side of the latch arm 17 to hold the latch in its engaged position. To release the latch for permitting the same to be swung out of engagement with the strip, the protuberance 27 is forced down out of the way of the sash by a pressure of a person's finger applied to the tongue 26.

70 From the foregoing description it will be understood that the latch 15 may be employed in cooperation with the strip 11 to fasten the two sashes of a window together in selected positions by simply swinging the latch into engagement within recesses of the strip. This may be done when the window is closed or when partly open. When the sashes in partly open positions are coupled by my fastener, the two sashes are movable together up or down to afford draft for ventilating purposes at the top and bottom of the window opening.

75 90 95 95 What I claim, is,—

100 A sash-fastener comprising a strip member provided with a series of recesses, and means to secure said plate to the side rail of an upper sash, a plate member adapted to be secured to the parting rail of the lower sash, said plate being slotted to provide a tongue element therefor, a latch member mounted upon said plate, said latch being formed of a plate folded upon itself to pro-

vide two arm elements adapted for engagement in spaced apart recesses of the strip, a means for pivotally connecting the latch to said plate to turn about an axis in laterally offset relation with the strip whereby the latch is capable of being swung into and out of engaged relations with said strip, and a catch provided upon the tongue ele-

ment of said plate for securing the latch in its engaged position and adapted to be disengaged from the latch by depressing said tongue element. 10

Signed at Seattle, Washington, this 31st day of October, 1925.

ARTHUR R. GLIDDEN.
